J. Connell

UNITED STATES PATENT OFFICE

THOMAS ALBERT BRIGGS CARVER, OF CHEADLE HULME, ENGLAND, ASSIGNOR TO
CARVER TEXTILE PATENTS LIMITED, OF MANCHESTER, ENGLAND, A BRITISH COM-
PANY

WARP STOP MOTION FOR LOOMS

Application filed July 14, 1928, Serial No. 232,637, and in Great Britain July 23, 1927.

My invention relates to mechanism where-
in the movement of an element closes an elec-
tric circuit to knock off a starting lever for
the purpose of stopping the mechanism, and
5 is applicable to, and will be described as ap-
plied to weaving looms having that type of
warp-stop motion in which the desired stop-
page of the loom on the breakage of a warp
thread is effected electrically, through the
10 action of detectors which engage with the
warp threads and which on the breakage of a
thread close a circuit through a knock off
motion to stop the loom. The particular ob-
ject of the invention is the provision of a
15 knock off motion which itself supplies a suffi-
cient force to throw off the starting and
stopping handle without assistance from a
moving part of the loom, and which can be
actuated from the source of supply at any
20 ordinary voltage and through the system of
wiring which may be already installed in
the mill in which the loom is situated, for any
purpose such as lighting or power.

According to the invention I provide a
25 spring which when unconstrained will main-
tain the loom handle or lever in the "off" or
stopped position, and I also provide a mag-
netic field which normally constrains the said
spring when the handle is moved to start
30 the loom, with means for neutralizing the
effect of the said magnetic field when a warp
thread breaks.

By this combination of spring and neutral-
izable magnetic field a very strong, rapid and
35 certain "off" movement of the loom handle,
immediately on a warp thread breaking, is as-
sured, the whole apparatus being self-con-
tained.

To provide the magnetic field an electro-
40 magnet is fitted in such a position that it will
through desired intermediate members main-
tain the spring in its constrained position by
means of a winding on the said magnet which
winding is in an electric circuit normally
45 closed. On the electro-magnet may be a fur-
ther winding opposed to the first, that is to
say, wound in the opposite direction, this op-
posed winding being included in a circuit
which is normally open, and closable by
50 movement of a warp thread detector. Thus,

when a warp thread breaks, constraint is re-
moved from the spring by the neutralizing
action of the opposed winding on the mag-
netic field.

In order to avoid passing a high voltage
55 through the warp thread detector system
with consequent danger from sparking, a
make and break device employing only a low
voltage may be utilized to close the opposed
winding circuit when a warp thread breaks.
60 A suitable make and break device may consist
of an armature which is normally held away
from a contact, this armature and contact be-
ing in the opposed winding circuit, and a
magnet which maintains the armature in this
65 position by a winding in a low voltage circuit.
On the magnet thus arranged a further op-
posed winding may be put, the warp thread
detector system being in the same circuit as
this opposed winding. On a detector closing
70 this circuit therefore, when a thread breaks,
the armature is no longer held by the mag-
net and is released to make contact with the
contact member and close the main opposed
winding circuit to remove constraint from
75 the loom handle spring.

The invention will now be fully described
with reference to the annexed diagrammatic
drawing, which shows a convenient arrange-
ment of loom handle, spring and magnetic
80 field, and circuits for the electro-magnet and
for the make and break device as above re-
ferred to. No part of the loom itself is shown
other than the loom handle.

Referring to this drawing, the loom handle
85 is shown at A, and when this handle passes
into and out of the notch B, thus being held
in the "on" position, it presses against a head
1 secured to a plunger which is slidably fitted
in fixed guides C. Surrounding the plunger
90 2 is a strong spring 3 abutting at one ex-
tremity against one of the fixed guides C and
at the other extremity against a collar 4
pinned on the plunger 2. When uncon-
strained therefore the spring 3 will press the
95 loom handle A into the "off" position through
plunger 2 and head 1.

On the end of the plunger 2 is formed or
secured an armature 5 which, when the loom
handle A and thus the plunger 2 are forced
100

into the "on" position seen in the drawing, enters a magnetic field of an electro-magnet 6 and is held close to the poles of the said magnet. The magnet is wound with two windings, one of which K is the energizing winding and is in circuit with a source of current supply S the circuit, as shown in the drawing being permanently closed—unless opened when the loom is not working—the other winding J being in a circuit which is normally open, and closable on breakage of a warp thread as hereinafter more fully referred to.

10 The armature 5 is therefore normally held against the poles of the magnet 6 during the working of the loom, to constrain the spring 3, and when a warp thread breaks and closes the circuit in which is included the coil J, the effect on armature 5 is neutralized and the spring 3 forcibly and rapidly knocks off the handle A.

15 As the passing of the necessarily strong current, required by winding J, through the detector electric circuit might cause danger from sparking, the make and break system shown in the drawing may be employed, as this will require only a very low voltage through the detectors proper. In the opposed winding J circuit is included an armature L which is normally held away from a contact member 8 by a magnet 9 which is wound with a winding 10 and energized from a secondary O of a stepped transformer at P which draws its current from the common source S. On the magnet 9 is an opposed winding 11, which is included in a circuit which also includes the detectors, indicated by X on the drawing. Normally therefore the armature L and the contact 8 are separated, but on the detector circuit closing 20 movement the winding 11 neutralizes the pull of the magnet 9 on armature L and the latter moves against the contact 8, thus closing the circuit in which is included the neutralizing winding J of the electro-magnet 6.

25 Equivalents may be employed instead of the make and break system just described. For instance the armature L may be normally in the position shown in the drawing and be drawn to make contact with the contact member 8, on the warp detector circuit being closed at X, by an electro-magnet, energized only on a warp thread breaking. The device shown and described above is however certain and simple in its action.

50 I claim:

1. In mechanism wherein a gap is adapted to be closed to close a stop motion electric circuit, a starting lever, a spring which when unconstrained forces the starting lever into mechanism-stopping position, a magnetic field which normally constrains the spring when the starting lever has been moved to its operative position, and means for neutralizing the magnetic field and thus its effect on

the spring, as a result of the closing of the stop motion circuit.

2. In mechanism wherein a gap is adapted to be closed to close a stop motion electric circuit, a starting lever, a spring which when unconstrained forces the starting lever into mechanism-stopping position, an armature on the starting lever, a magnet and energizing winding thereon forming a magnetic field for the armature, and a further and opposed winding on the magnet which opposed winding is energized by the closing of the stop motion circuit.

3. In mechanism wherein a gap is adapted to be closed to close a stop motion electric circuit, a starting lever, a spring which when unconstrained forces the starting lever into mechanism-stopping position, an armature on the starting lever, a magnet and energizing winding thereon forming a magnetic field for the armature, a further and opposed winding on the magnet and included in a separate circuit to that of the first winding, a second magnet having low voltage energizing winding; an armature in the magnetic field of such second magnet, such armature maintaining open the circuit which includes the opposed winding of the first magnet, and means for neutralizing the low voltage magnetic field by the closing of the stop motion circuit.

4. In mechanism wherein a gap is adapted to be closed to close a stop motion electric circuit, a starting lever, a spring which when unconstrained forces the starting lever into mechanism-stopping position, an armature on the starting lever, a magnet and energizing winding thereon forming a magnetic field for the armature, a further and opposed winding on the magnet and included in a separate circuit to that of the first winding, a second magnet having a low voltage energizing winding, an armature in the magnetic field of such second magnet, such armature maintaining open the circuit which includes the opposed winding of the first magnet, and a further low voltage winding on the second magnet, opposed to the energizing winding thereon and included in the stop motion circuit.

55 In testimony whereof I have hereunto set my hand.

THOMAS ALBERT BRIGGS CARVER.
